UNITED STATES PATENT OFFICE.

JESSE KRIEG AND DANIEL Z. PADGETT, OF ADAMSTOWN, MARYLAND.

GATE.

1,115,686.

Specification of Letters Patent.

Patented Nov. 3, 1914.

Application filed April 6, 1914. Serial No. 829,955.

To all whom it may concern:

Be it known that we, JESSE KRIEG and DANIEL Z. PADGETT, citizens of the United States, residing at Adamstown, in the county of Frederick and State of Maryland, have invented certain new and useful Improvements in Gates; and we do declare the following to be a full, clear, and exact description of the invention, such as will enable others skilled in the art to which it appertains to make and use the same.

This invention relates to new and useful improvements in gates and more particularly to a farm gate and has for its object 15 to provide means whereby the horizontal position of the gate may be varied or changed at will so as to raise the free end thereof to any desired height above the ground.

20 A further object of the invention resides in providing an improved hinge construction for engagement with the lower portion of the gate whereby said hinge may be adjustably secured to the gate for retaining 25 the latter in its adjusted position.

Still another object of the invention resides in providing an improved means for actuating the hinge and gate for the purpose of raising and lowering the latter with 30 respect to the ground.

Another object is to provide a device which is simple and durable in construction, inexpensive to manufacture and one which will be very efficient in use.

35 With these and other objects in view, our invention consists in the novel features of construction, combination and arrangement of parts as will be hereinafter referred to and more particularly set forth in the specification and claims.

40 In the accompanying drawings forming a part of this application:—Figure 1 is a side elevation of the gate applied to use with the improved hinge construction thereon, showing in dotted lines a raised position of said gate; Fig. 2 is a horizontal section therethrough as seen on line 2—2 of Fig. 1; Fig. 3 is a vertical transverse section through the same as seen on line 3—3 of Fig. 1; Fig. 4 is a similar view as seen on line 4—4 of Fig. 1; and Fig. 5 is a detail elevation of a slight modification for use in connection with this gate.

45 In describing the invention we shall refer 55 to the drawing in which similar reference

characters designate corresponding parts throughout the several views and in which— 1 indicates a gate of any desired size and construction the same being adapted to swing between the gate posts 2 and 3, the former being the hinge post. Said post 2 is provided adjacent its upper and lower ends with the usual pintles 4 which are provided for hinging gates thereto and one of the hinges between the gate and post 60 2 is of the ordinary strap type as indicated at 5, the same being secured to the gate by means of a bolt 6 and having the eye thereof, as usual, engaged on the upper pintle 4 on the post 2. The lower hinge indicated in 70 the drawing at 7 is also of the ordinary strap type having a portion thereof bent upon itself to form a usual eye for engagement with the lower pintle 4 on said post 2 and the shank or longer arm of said strap 75 hinge is slotted adjacent its outer end as indicated at 8. It must be here stated that the eyes of the strap hinges 5 and 7 are somewhat loosely engaged with the pintles 4 affording loose hinge connection between 80 the gate and the hinge post. Projecting through the gate and through the slot 8 of said hinge 7 is a bolt 9 having an ordinary wing nut 10 engaged with the threaded outer end thereof whereby to clamp the 85 free end of said strap hinge tightly against the side of the gate and thereby prevent movement of the two relatively to each other. It will be seen from this construction that the gate is capable of movement 90 with respect to the strap hinge 7 and the two may be secured together in various adjusted positions with respect to one another. But we have provided a means for guiding the one in its movement with respect to the 95 other. To this end we provide a guide plate 11 which is held against the outer face of the strap hinge 7 by means of bolts 12 engaged with said plate and extending through the gate member 1 above and below 100 said strap hinge 7, the free ends of said bolts being engaged with nuts 13. While the guide plate 11 affords a guiding means for the strap hinge 7 as the gate is moved with respect thereto, it will also be seen that the 105 same may be used for affording clamping means between the gate and strap hinge to aid or assist the clamping of said hinge engaged as described above.

110 In view of the particular construction

above described and claimed in the drawing, it will be seen that any desired movement of the parts may be had, thereby permitting the free end of the gate to be raised so as to pass over a snow drift or to permit stock of a small size to pass through the gateway without permitting larger animals to pass therethrough. It will also permit the free end of the gate to be raised in case the hinge post should incline so as to lower the free end of the gate, as frequently occurs with such structures. While these adjustments may be readily made, we have provided a specific means for manually raising and lowering the gate which means will simplify the operation materially and be of great advantage to the operator. To this end, a lever 14 is provided, the one end thereof being curved or bent as shown at 15 and said lever in the curved portion thereof adjacent the free end of the same is fulcrumed as indicated at 16 on the strap hinge 7. The fulcrum indicated at 16 is represented in the drawing as a threaded bolt engaged with a threaded opening in the strap hinge 7 and a spacing washer 17 is mounted on said bolt or fulcrum member 16 between the face of said strap hinge 7 and the lever 14. Engaged with the threaded outer end of said fulcrum 16 is a nut 18 which when turned home properly secures said lever 14 in position thereon.

Engaged with the extreme lower free end of the curved portion of said lever 14 is a link 19, the opposite end of said link being loosely engaged with the stop or bolt 9 under the wing nut 10. It will thus be seen that by an actuation of said lever 14, said gate may be actuated with respect to the hinge 7 and thus the outer end of said gate may be raised and lowered as desired. In order to retain this gate in various adjusted positions or in other words at various heights to which the same may be adjusted, a plate or bar 20 is provided with a plurality of spaced openings 22 and a peg or stud 23 is provided for reception in the same. The outer end of the actuating lever 14 passes over the outer face of the bar 20 and when said lever is disposed to the position adjusting the gate to its desired position, the peg may be inserted in the opening 23 just below said lever 14, thus retaining the latter in its adjusted position and retaining the gate in the desired position.

In order to permit the above described movement or adjustment of the free end of the gate without affecting the latch mechanism thereof, a hook shaped latch member 24 is provided on the post 3. The free end of this latch member is inclined rearwardly as shown at 25 which will permit the free end of the gate engaging therewith, irrespective of its height or vertical adjustment.

In Fig. 5 we have shown a slight modification of a means for retaining the lever 14

in any adjusted position. In this modification, a link chain 26 is provided the same being secured at its upper end to the gate about centrally thereof and adjacent the upper edge of said gate. The links each form means for the reception of the outer end of the lever 14 therein and obviously admits of the retention of said lever in any adjusted position. The device is otherwise formed as described in connection with the above mentioned form.

In operation, assuming that this device is entirely set up and ready for use, should it be desired to raise the outer end of the gate to permit smaller animals in the stock yard to pass thereunder and at the same time prevent larger animals from passing through the gate way, it is only necessary to grasp the outer end of the lever 14 and raise upwardly thereon. Such an actuation causes the lower or inner end of said lever 14 to force outwardly on the link 9 which causes the gate to be moved outwardly and upwardly with respect to the strap hinge 7. When said lever has been moved to the position which positions the gate as desired, the stud or peg 23 may be inserted in the proper opening 22, thus retaining said lever in its adjusted position. If desired, at this time the wing nut 10 may be turned home tightly, thus clamping the link 9 tightly against the strap hinge and securing said gate in its adjusted position with respect to the hinge without further securing means. Of course, if it is desired to raise the gate to the full degree, the outer end of said lever 14 is raised until the same may be engaged with the hook member 21 at the upper end of the gate. In the lowering of the gate to its initial position, the operation is reversed and the construction of the parts is such that when the gate is lowered the one edge of said guide plate 11 will contact with the spacing washer 17 on the bolt or fulcrum member 16 thus limiting the downward movement of said gate with respect to the hinge member. When these parts contact with one another as described, the gate member is in its horizontal and initial position.

While we have described a means for actuating, that is raising and lowering, the gate with respect to the hinge post, it will be understood that this means may be entirely omitted if desired. It is apparent that without the use of the link and the actuating lever and their adjunctive parts this gate may be moved with respect to the strap hinge 7 to raise or lower the outer end thereof and may be secured in any adjusted position by the turning home of the wing nut 10 on the bolt 9.

From the foregoing, it will be seen that we have provided a simple, inexpensive and effective means for carrying out the object of the invention and while we have particu-

larly described the elements best adapted to perform the functions set forth it is obvious that various changes in form, proportions and in the minor details of construction may be resorted to within the scope of the appended claims, without departing from the spirit or sacrificing any of the principles of the invention.

Having thus described our invention what we claim is:—

1. The combination with a stationary member; of a swinging member, a pair of strap hinges operatively connecting said members one with the other, the lower of said strap hinges being slotted, a stud carried on the swinging member and projecting through the slot of said last mentioned hinge member to afford adjustment of the swinging member with respect to the stationary member, means in connection with said last mentioned strap hinge and said stud for manually adjusting said swinging member and additional means in connection with the last referred to means for retaining said members in any adjusted position.

2. The combination with a stationary member; of a swinging member, a pair of strap hinges operatively connecting said members one with the other, the lower of said strap hinges being slotted, a stud carried on the swinging member and projected through the slot of said last mentioned hinge member whereby to provide a loose connection between the hinge member and swinging member and affording means for the adjustment of the swinging member with respect to the stationary member, a lever fulcrumed adjacent one end thereof on said last mentioned hinge member, a link pivotally connected at its one end with the last mentioned end of said lever and having its opposite end engaged with the aforesaid stud on said swinging member, whereby to adjust said swinging member upon the actuation of said lever, and means for retaining said lever and correspondingly said swinging member in any adjusted position.

3. The combination of a stationary member; of a swinging member, a pair of strap hinges operatively connecting said members one with the other, one of said hinges hav-

ing a slot therein, a pin projected from said swinging member through the slot in said last mentioned hinge member, affording 55 movement between the swinging member and said hinge, an actuating lever fulcrumed adjacent its inner end on said last mentioned hinge member, a link having pivotal connection at its one end with the extreme inner end of said actuating lever, the opposite end of said link having engagement with the aforesaid pin on said swinging member, means engaged with said pin for retaining the last mentioned end of said 60 link in position thereon, said means also adapted for the retention of said swinging member in any position to which the same may be adjusted with respect to the last mentioned hinge, and additional means in 65 connection with said actuating lever for retaining the latter and correspondingly said swinging member in any adjusted position.

4. The combination with a stationary member; of a swinging member, a pair of strap hinges operatively connecting said members one with the other, the lower of said strap hinges having movable engagement with said swinging member, a guide member mounted on the swinging member receiving said last mentioned strap hinge therethrough, a lever fulcrumed adjacent its inner end on said last mentioned strap hinge, a spacing collar arranged between said lever and the last mentioned strap hinge, said spacing collar being adapted to contact with said guide member and swinging member to limit the movement in one direction of said swinging member with respect to the last mentioned hinge, linking 80 means between the extreme inner end of said actuating lever and said swinging member to adjust the latter with respect to the last mentioned hinge, and means for retaining said lever and correspondingly said swinging member in any adjusted position. 85

In testimony whereof we have hereunto set our hands in presence of two subscribing witnesses.

JESSE KRIEG.
